US0D1034528S

(12) **United States Design Patent** (10) **Patent No.:** **US D1,034,528 S**
(45) **Date of Patent:** **** Jul. 9, 2024**

(54) **SPEAKER**

(71) Applicants: **Franco L D'Ascanio**, Key Colony Beach, FL (US); **Sean P Snowden**, Marathon, FL (US); **Harold M Zimmermann**, Riverton, NJ (US); **Igor Levitsky**, Richmond Hill (CA)

(72) Inventors: **Franco L D'Ascanio**, Key Colony Beach, FL (US); **Sean P Snowden**, Marathon, FL (US); **Harold M Zimmermann**, Riverton, NJ (US); **Igor Levitsky**, Richmond Hill (CA)

(73) Assignee: **COASTAL SOURCE, LLC**, Marathon, FL (US)

(**) Term: **15 Years**

(21) Appl. No.: **29/929,114**

(22) Filed: **Feb. 20, 2024**

(51) **LOC (14) Cl.** **14-01**
